UNITED STATES PATENT OFFICE.

ALBERT B. PULLMAN, OF CHICAGO, ILLINOIS.

DRAW-BAR FOR RAILWAY-CARS.

SPECIFICATION forming part of Letters Patent No. 239,272, dated March 22, 1881.

Application filed October 18, 1880. (No model.)

To all whom it may concern:

Be it known that I, ALBERT B. PULLMAN, of Chicago, in the county of Cook and State of Illinois, have invented an Improvement in 5 Draw-Bars for Railway-Cars, of which the following is a specification.

My invention relates to improvements in the construction of draw-bars for railway-cars; and it consists in the peculiar construction and 10 arrangement of the parts, as hereinafter more fully set forth.

Figure 1 is a plan of the bottom of sections of two coupled cars, showing their position in passing a curve of short radius. Fig. 2 is an 15 enlarged perspective view of my improved draw-bar inverted. Fig. 3 is a vertical central longitudinal section through the front end of the draw-bar. Fig. 4 is a like section of the opposite end of the same.

20 In the accompanying drawings, which form a part of this specification, A represents the body-bolster of a car, and B the platforms, rounded at their adjoining ends, as shown in Fig. 1, to allow the cars to pass around curves 25 of short radius.

C is the king-bolt or draw-pin with which each car is provided at each end thereof, and to which the coupling device hereinafter described is pivoted.

30 The draw-bar is constructed as follows:

D is a plate, the free end of which is perforated to engage with the king-bolt, while the opposite end is provided with a lip, a, which engages with a suitable slot in the plate E, 35 which is secured to the front end of the plate D by means of the bolts and nuts b.

F are two yokes secured to the under side of the plate E, to inclose and hold in position the resistance-plates c, between which is placed 40 the coiled spring d.

G is the draw-bar proper, which is preferably made of iron with a wooden filling, H. The rear end of the draw-bar terminates in a rectangular loop, I, which has a longitudinal movement between the yokes F. A bolt, e, passes through the rear vertical end of this loop and through the resistance-plates c and the coil-spring, to hold the parts together, the draw-bar being controlled in its longitudinal movements by the operation of the coil-spring in 45 the usual manner in constructions for a simi-

lar purpose. The front end of the draw-bar terminates in the head J, which has a rectangular opening, f, longitudinally through the same, sufficiently large to allow the coupling-bar K 55 to freely enter, with but little play, and pass through until the end of such bar impinges against the stop g, in which position it is secured by the coupling-pin h, which passes through the head and bar for that purpose. 60

A sector-support, L, is suitably suspended below the platform, near its front end, and is rigidly secured thereto by proper bolts, and its office is to support the front end of the draw-bar, and at the same time to allow of a radial 65 movement of this end of the draw-bar to the right or left, as occasion may require, the king-bolt being the axis of such movement.

A spring, M, is secured to the under side of the draw-bar, and to the front end of this spring 70 is secured the shoe N, which travels, in the radial movement of the draw-bar, upon the upper face of the sector.

The coupling-bar K is a rigid bar, fitting 75 into the head of the draw-bar, with very little play therein, and near each of its ends it is provided with a hole for the coupling-pin, and so arranged that when two cars are coupled together the ends of the heads of the draw-bar are brought into close and rigid juxtaposition, 80 as shown in Fig. 1.

By this construction and operation all the advantages hereinbefore recited are obtained; and it will, perhaps, be needless to add that each end of the car is provided with the coupling described. 85

What I claim as my invention is—

1. In combination with a car-platform having pendent therefrom a sector, a draw-bar provided with a spring and shoe, substantially 90 as and for the purpose specified.

2. The combination, with the perforated plate D, pivoted to the platform, and slotted plate E, secured to the front end of said plate and provided with the yokes F, of the draw-bar G, terminating in the rectangular loop I, bolt e, resistance-plates c, and coiled spring d, substantially as described, and for the purpose 95 set forth.

3. The combination, with the pivoted perforated plate D and slotted plate E, secured thereto and provided with the yokes F, of the 90

draw-bar G, having the end loop, I, resistance-plates c, bolt e, spring d, spring M, provided with shoe N, and sector-plate L, substantially as described, and for the purpose set forth.

5 4. The combination, with the perforated pivoted plate D and slotted plate E, secured thereto and provided with the yokes F, of the draw-bar G, provided with the loop I and stop g, rigid coupling-bar K, resistance-plates c, and spring d, substantially as described, and for the purpose set forth.

5. The coupling-bar G, made of iron, with a wooden filling, H, stop g, loop I, and spring M, carrying on its free end the shoe N, substantially as described, and for the purpose set 15 forth.

ALBERT B. PULLMAN.
